UNITED STATES PATENT OFFICE.

ALFRED W. EMERSON, OF MILLBRIDGE, MAINE.

WINDOW-SCREEN.

Specification of Letters Patent. Patented Sept. 30, 1919.

1,317,361.

Application filed June 1, 1916. Serial No. 101,068.

To all whom it may concern:

Be it known that I, ALFRED W. EMERSON, a citizen of the United States, residing at Millbridge, in the county of Washington, 5 State of Maine, have invented certain new and useful Improvements in Window-Screens; and I do hereby declare the following to be a full, clear, and exact description of the invention, such as will enable others 10 skilled in the art to which it appertains to make and use the same.

This invention relates to a window screen.

An object of the invention resides in the 15 provision of a screen which is so constructed that it may be raised to various heights with the raising and the lowering of the window and so that it will be held in its raised position by the window.

20 A further object of the invention resides in so constructing the device that it may be conveniently rolled when not in use.

With these and other objects in view, such as will appear as my description progresses, 25 my invention comprises the combination and arrangement of parts as set forth in and falling within the scope of the appended claims.

In the drawing:

30 Figure 1 is an elevational view of my device showing the same mounted on a window frame and showing a portion of the sash broken away;

Fig. 2 is a vertical sectional view through 35 the device showing the manner in which it engages the window sash;

Fig. 3 is a detail of the rolling means, and

Fig. 4 is a horizontal sectional view looking upon the upper edge of the screen.

40 In the drawing I have illustrated a window frame 1 and a sash 2. A roller 3 is mounted at the outside of the frame and is inclosed in a cover or casing 4. A screen member 5 is provided which has on its upper 45 and lower edges reinforcing strips 6 and 7, of metal and on its side edges flexible strips 8 forming bindings and from which metallic reinforcing plates 9 extend inwardly and prevent the bulging of the screen 5.

50 The ends of strip 6 on the upper end of the screen 5 extend into slots 10 which are formed between pairs of guide members 11 which are secured to the sides of the window frame. This upper strip 6 is provided on 55 each side with a strip 12, the ends of which strips 12 bear against the edges of the guides

11 and slide thereon. Thus the screen 5 may be raised or lowered at will. On one end of the roller 3 a pulley 13 is secured on which a flexible operating member 14 is wound by means of which the screen may be rewound upon the roller, the operating member extending to the inside of the window.

In order that the screen may be maintained in the position illustrated and so that the flies will be prevented from entering between the upper edge of the screen and the lower bar of the sash, I have secured a wedge shaped strip 15 to the innermost of 65 the strips 12, which strip 15 bears against the side faces of opposite guides 11 and increases in width from its upper to its lower edge. The adjacent face of the sash 2 is beveled, as at 16, so that when the screen is 70 raised after the inner sash has been raised, the strip 15 will be wedged between the lower bar of the sash 2 and the guides 11 and consequently the screen will be held in 75 its adjusted position to cover the open lower 80 part of the window and the flies will be prevented from entering the room.

While I have illustrated and described a particular embodiment of my invention, it has merely been for the sake of convenience 85 and I do not wish to be limited to that particular embodiment as it is obvious that numerous changes may be made in the details of construction without departing from the spirit of the invention or exceeding the 90 scope of the appended claims.

What I claim is:

1. The combination with a window frame and sash, of a roller mounted on the frame, a screen member secured to the roller and windable thereon, a pair of guides mounted on the frame, between which guides said screen is adapted to slide and a wedge member carried by the upper edge of the screen and adapted to wedge between the lower 95 edge of the lower sash and the said guide.

2. The combination with a window frame and sash, of a pair of guide members mounted on each side of the frame, a vertically slidable screen mounted between said 100 guide members, a strip secured to the upper edge of the screen and contacting with the inner face of a guide member of each pair, which strip is wedge shaped and increases in width from its upper to its lower edge, 110 the adjacent face of the lower sash being beveled whereby the strip may be wedged

- between said guide members and the sash to maintain the screen in raised position and means for withdrawing the strip from between the sash and the guide members.
5. 3. The combination with a window frame and sashes; of a roller mounted on the frame, a screen member secured to the roller and windable thereon, a pair of guides mounted on the frame and between which
- 10 said screen is adapted to slide independently of and in alinement with one of the sashes, and a wedge member carried by the free

edge of the screen and adapted to wedge between the adjacent edge of the other sash and said guide, when the latter sash is open ¹⁵ and disposed in alinement with the first sash, said wedge member and screen being freed upon closing the second sash.

In testimony whereof, I affix my signature in the presence of two witnesses.

ALFRED W. EMERSON.

Witnesses:

BART W. BROWN,
FRANK N. BROWN.
